UNITED STATES PATENT OFFICE.

ANDRÉ JULES MICHELIN, OF PARIS, FRANCE.

DESIGN FOR AN AUTOMOBILE-TOOL.

45,644.

Specification for Design.

Patented Apr. 21, 1914.

Application filed November 3, 1913. Serial No. 799,038. Term of patent 3½ years.

To all whom it may concern:

Be it known that I, ANDRÉ JULES MICHELIN, a citizen of the Republic of France, residing at Paris, France, have invented a new, original, and ornamental Design for an Automobile-Tool, of which the following is a specification, reference being had to the accompanying drawings, forming part thereof.

Figure 1 is a side elevation; and Fig. 2 a

plan view of a tool showing my new design. Fig. 3 is an inverted plan view of the tool shown in Figs. 1 and 2.

I claim:

The ornamental design for an automobile tool, as shown.

ANDRÉ JULES MICHELIN.
